CONDUIT CLEANER

Paul P. M. Dubesclard, Buffalo, N. Y., assignor to
Katherine V. Deem, Buffalo, N. Y.

Application May 12, 1937, Serial No. 142,307

1 Claim. (Cl. 15—104.30)

This invention pertains to conduit cleaners of a type generally similar to that constituting the subject matter of U. S. Patent 2,074,213, issued March 16, 1937, upon which the present device 5 constitutes an improvement.

The primary object of the present invention is to provide, in a conduit cleaner of the type including a rotary brush, a source of power, such as a motor, and flexible means operatively connecting said brush to said source of power, novel means adapted to travel in the conduit being cleaned for yieldingly supporting the drive means centrally in said conduit.

Other objects of the invention are to provide 15 a conduit cleaner of the character described which will be comparatively simple in construction, strong, durable, highly efficient and reliable in use, compact and which may be manufactured at low cost.

20 All of the foregoing and still further objects and advantages of the invention will become apparent from a study of the following specification, taken in connection with the accompanying drawing wherein like characters of reference 25 designate corresponding parts throughout the several views, and wherein:

Figure 1 is a view in side elevation of the present invention, showing same operating in a conduit, the latter being shown in longitudinal 30 section.

Figure 2 is a cross sectional view, taken substantially on the line 2—2 of Fig. 1.

Figure 3 is a view in vertical longitudinal section, taken substantially on the line 3—3 of 35 Fig. 2.

Referring now to the drawing in detail, it will be seen that the embodiment of the present invention which has been illustrated comprises an electric motor 1 of suitable horse power. Of course, the motor 1 may be connected with any suitable source of current supply. Fixedly secured at one end to the electric motor 1 is a flexible tubular housing 2. The other end of the flexible housing 2 is rotatably connected to a brush 3 which, as it is rotated, is adapted to be drawn through the conduit to be cleaned, as at 4. The flexible housing 2 encloses a flexible drive shaft or chain 5 having one end operatively connected to the electric motor 1 for actuation there- 45 by and its other end connected to the brush 3 for rotating said brush.

The reference numeral 6 designates a suitable winch on which a flexible cable 7 is adapted to be wound. The cable 7 is rotatably connected 50 to one end of the brush 3 by a suitable swivel 8.

The winch 6 comprises an actuating crank 9 but, of course, any suitable means may be provided for operating said winch. As will be readily apparent, the cable 7, when it is wound on the winch 6, draws the brush 3 through the conduit 4. 5

Fixed on the flexible housing 2, adjacent the rotary brush 3, is a metallic sleeve 10. A set screw 11 secures the sleeve 10 in position on the flexible housing 2. Secured by a set screw 12 on the sleeve 10 is a collar 13 of polygonal cross-section from certain of the flat faces of which pairs of integral ears 14 project. Pivotally mounted between the pairs of ears 14 are arms 15 which are yieldingly urged outwardly by springs 16. The free ends of the arms 15 are 15 bifurcated and journaled therein are rollers 17 which are adapted to travel on the inner periphery of the conduit 4.

It will thus be seen that a means has been provided for supporting the drive shaft and the 20 housing therefor substantially centrally in the conduit 4 at a point adjacent the rotating brush 3. It will also be noted that the construction and arrangement of this supporting unit is such that it will readily adapt itself to various sizes 25 of conduits within a given range. Still further, the rollers 17 will readily pass or ride over any irregularities or obstructions that may be encountered in the conduit. The collar or sleeve 10 is placed on the flexible tubular shaft 2 at 30 the desired distance from the brush 3 and is fastened in position by the screw 11. This sleeve 10 forms an annular seat for the collar 13 which is fastened to the sleeve by the screw 12. Thus when it is necessary to use a different sized device or pilot composed of the collar 13 and the roller bearing arms 15, for a different sized pipe or conduit, the collar 13 in use is removed and another collar which forms part of a different 35 sized device or pilot is placed on the sleeve 10 40 and fastened in position. This renders it unnecessary to remove the sleeve 10 each time a different sized device is to be attached to the shaft 2 for use with a different sized conduit and this is desirable as the removal and replacing of the sleeve 10 on the flexible pipe 2 would soon injure the rubber covering of the same, and as the collar 13 is of such larger internal diameter than the external diameter of the shaft 2 this collar 13 can be readily placed over the 45 shaft 2 without injuring the same and this arrangement also prevents injury to the shaft cover which would be caused by frequent setting of the screw 11. In other words, the sleeve 10 remains in semi-permanent location and whenever 50

55

it is desired to use the device on a conduit of a different size from that on which the device is last used, it is simply necessary to remove the collar and replace it by a collar of a different 5 sized device which, of course, includes a collar and the spring actuated roller carrying arms 17.

It is believed that the many advantages of a conduit cleaner embodying the present invention will be readily understood and although a 10 preferred form of the improved device is as illustrated and described, it is to be understood that changes in the details of construction and in the construction and in the combination and arrangement of parts may be resorted to which 15 will fall within the scope of the invention as claimed.

What is claimed is:

Means for supporting the flexible shaft of a conduit cleaner in a conduit, comprising a sleeve through which a portion of the shaft passes, means for clamping the sleeve to the shaft, a 5 collar fitting around the sleeve and having radiating pairs of ears thereon, an arm pivoted between the ears of each pair, a roller at the outer end of each arm, means for removably fastening the collar to the sleeve and spring 10 means for forcing the arms outwardly to cause the rollers to yieldably engage the internal walls of a conduit, said pivot for the arms constituting anchoring means for the spring means.

PAUL P. M. DUBOSCLARD.
